CHARLES HOLTZHAUER, OF PARIS, FRANCE, ASSIGNOR TO LA SOCIETE DE CONSTRUCTION DES BATIGNOLLES, OF PARIS, FRANCE.

SMOOTH-BORE GUN.

1,309,202.

Specification of Letters Patent.

Patented July 8, 1919.

Application filed July 17, 1918. Serial No. 245,392.

To all whom it may concern:

Be it known that I, CHARLES HOLTZHAUER, a citizen of the Republic of France, and resident of Paris, France, (post-office address 7 Rue Balagny, Paris,) have invented a new and useful Improvement in Smooth-Bore Guns, which improvements are fully set forth in the following specification.

This invention relates to smooth-bore guns of the muzzle loading type, that is to say of the type in which the projectile alone or both the projectile and the powder charge are loaded into the gun from the muzzle, the invention having particular reference to such guns known as trench mortars. Numerous types of guns have been constructed in which a chamber is formed between the explosion or powder charge chamber and the base of the projectile for the expansion 20 of the gases resulting from the explosion of the powder charge.

According to the present invention the smooth-bore muzzle loading gun consists of a thick-walled rear part, constituting the explosion chamber, situated in line with and forming part of a thin-walled barrel which is of larger bore than the explosion chamber and which is adapted to receive a thin-walled projectile having a tail piece which 30 bears against an abutment formed in the gun. In this way there is provided in the rear part of the barrel between the explosion chamber and the base of the projectile a space constituting an expansion 35 chamber having a volume which is predetermined by the length of the tail piece and which is maintained constant with each projectile fired (assuming that the tail pieces are of the same length and the bases of the 40 projectiles are similarly shaped) by loading each projectile into the barrel from the muzzle until the tail piece bears against the aforesaid abutment.

In order that the said invention may be clearly understood and readily carried into effect it will be fully described with reference to the accompanying drawings, in which:—

Figure 1 is a longitudinal section showing 50 the barrel of a trench mortar with the projectile in position therein.

Fig. 2 is a cross-section taken on the line A—A of Fig. 1.

Fig. 3 is a view similar to Fig. 2, but

showing a cylindrical tail piece carried by 55 the projectile.

The mortar is composed of two parts:—

1. The rear part or thick-walled breech end *a* which is formed with an explosion chamber *c* for the propelling charge. The 60 capacity of this chamber is so determined as to insure a good deflagration of the charge and the thickness of its walls is such that they will withstand the high pressures obtained by the use of modern smokeless 65 powder. The trunnions may form part of the said breech end.

2. The forward part or thin-walled barrel *b* connected to or made integral with the breech end.

The projectile comprises a thin casing *e* of part-spherical form at the forward end and tapering at the rear, and a cruciform tail piece *f* or a cylindrical tail piece *g* (Fig. 3) welded to the rear part. The dimensions 75 of this tail piece permit of the introduction of the projectile into the barrel from the muzzle, the rear end of the tail piece bearing against a suitable shoulder as shown by Fig. 1. There is thus formed between the 80 explosion chamber and the base of the projectile a chamber *d* having a length equal to that of the tail piece and in which the powder gases are confined and expand freely in order to reduce the pressure until the 85 value of the latter is compatible with the thickness of the walls of the gun barrel and of the projectile, thus forming what may be termed a low or reduced pressure gun. At the forward end of the projectile, is located 90 the percussion cap or other device for effecting the detonation of the bursting charge of the projectile.

What I claim and desire to secure by Letters Patent of the United States is:—

A smooth-bore gun of the muzzle-loading type, comprising a thick-walled rear part constituting the explosion chamber, a thin-walled barrel of larger bore than the bore of the explosion chamber disposed co-axially with the said rear part, and an abutment formed in the gun at the junction of the rear part and the barrel consequent upon the difference between the diameters of said bores; in combination with a projectile adapted to be received in said barrel and having a rearwardly extending tail-piece which bears at its free end against

the abutment whereby the movement of the projectile inwardly of the barrel is limited and the base of the projectile is normally spaced a distance forward of the explosion chamber, so as to form in the rear part of the barrel between said projectile base and said explosion chamber when the projectile is in place in the barrel an expansion chamber of predetermined volume and of the same diameter as the bore of the barrel wherein the powder gases freely expand and

are confined until the pressure within the barrel is reduced to the point where it is compatible with the thickness of the wall of said barrel; substantially as described. 15

In testimony whereof I have signed this specification in the presence of two subscribing witnesses.

CHARLES HOLTZHAUER.
